DESIGN FOR A FOOD MINCER

Mario A. Besozzi, Beechhurst, N. Y.

Application October 18, 1946, Serial No. 134,039

Term of patent 3½ years

(Cl. D44—29)

To all whom it may concern:

Be it known that I, Mario A. Besozzi, a citizen of the United States, residing at Beechhurst, in the county of Queens and State of New York, have invented a new, original, and ornamental Design for a Food Mincer, of which the following is a specification, reference being had to the accompanying drawing, forming a part thereof.

Fig. 1 is a front elevational view of a food mincer, showing my new design.

Fig. 2 is a side view thereof.

I claim:

The ornamental design for a food mincer, substantially as shown.

MARIO A. BESOZZI.
